UNITED STATES PATENT OFFICE.

JOHN GILLILAND, OF PAYNEVILLE, KENTUCKY, ASSIGNOR TO HIMSELF,
WILLIAM R. HAISE, SAMUEL E. HAISE, DANIEL BAYRINGER, THOMAS I.
RHOADES, AND JOHN G. WILLIAMS, ALL OF SAME PLACE.

TWIN SPRING FOR BED-BOTTOMS.

SPECIFICATION forming part of Letters Patent No. 248,305, dated October 18, 1881.

Application filed August 27, 1881. (Model.)

To all whom it may concern:

Be it known that I, JOHN GILLILAND, a citizen of the United States of America, residing at Payneville, in the county of Meade and State of Kentucky, have invented a certain new and useful Improvement in Twin Springs for Bed-Bottoms; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

The object of my invention is to so form the connecting portion of a twin spring that the bearing-surface thereof shall be continuous throughout the entire space between the upper terminal coils of each spring of the pair, so that a bed-bottom composed of twin springs of the form herein shown and described shall present a continuous supporting-surface for the mattress, and this without the use of separate connecting links or bars extending from spring to spring.

My invention properly belongs to that class wherein the material forming the springs is bent into various shapes at that portion which joins the two upper spirals of the springs—that is, the upper spiral of each spring of the pair is continued or integrally merged into a connecting portion in various forms and for various purposes; and my said invention consists in the form of said connecting portion, as shown and described, and as hereinafter specifically set forth in the claim.

The drawing represents a plan of a twin spring embodying my invention, and A represents what I shall, for convenience in description, term the "right" spring of the pair, and B the left. The upper spiral of the right spring is inwardly curved in V form, as is also the up-

per spiral of the left spring, which is curved oppositely to the right, and the V of each spiral is connected with the other by means of a diagonally-disposed S-shaped bar.

Referring more particularly to the drawing, and imagining lines drawn from the upper spiral of one spring to that of the other on each side, as x y, it will be seen that the V's b and c each point inwardly and terminate at about a central line parallel with lines x and y, and reach outwardly the lines x and y, respectively, and are connected by the S-shaped bar a, diagonally disposed, as above stated.

The benefits accruing from this construction are not only a uniform bearing-surface, but when pressure or weight is placed wholly on one or the other of the V's it is more evenly distributed to other portions of the connection and the springs than would be the case were the connection shaped with less re-entering curves and outside loops.

I am aware that twin springs are not new, and that their connecting portions have been extended beyond the side lines, x and y, of the spirals for the purpose of providing means for connecting rows of springs, and that they have been provided with one loop on one and two loops on the other side, and I do not claim such as of my invention; but

What I do claim as new, and desire to secure by Letters Patent, is—

The twin springs A B, having their integral connecting-wire bent into two inwardly-projecting V's, b and c, joined by a diagonally-disposed S-bar, a, substantially as shown and described.

In testimony whereof I have affixed my signature in presence of two witnesses.

JOHN GILLILAND.
